UNITED STATES PATENT OFFICE.

ALBERT SCHMID, OF ALLEGHENY, ASSIGNOR TO THE WESTINGHOUSE ELECTRIC AND MANUFACTURING COMPANY, OF PITTSBURG, PENNSYLVANIA.

DESIGN FOR A FRAME FOR ELECTRIC MACHINES.

SPECIFICATION forming part of Design No. 21,416, dated March 22, 1892.

Application filed January 28, 1892. Serial No. 419,614. Term of patent 14 years.

To all whom it may concern:

Be it known that I, ALBERT SCHMID, a citizen of the United States, residing in Allegheny, in the county of Allegheny, State of Pennsylvania, have invented a new and original Design for the Frame of a Machine, of which the following is a specification, reference being had to the accompanying drawings, forming a part thereof.

10 Figure 1 is a perspective view of the frame, and Fig. 2 is a side elevation thereof.

The leading feature of the design is the general configuration of the frame with the extensions which constitute the supporting-pillars for a shaft. A represents this frame. The bottom portion is of a somewhat rectangular shape, being rounded, however, at the corners, as indicated at a. The central portion is cylindrical in form. It is located nearer to one end 15 of the base than the other, and its sides, resting upon the base, are curved, as indicated at

a^2 . The pillars a^2 rise from the bottom portion or base at opposite ends. The sides of these pillars are of curved contour, as shown at c, gradually sinking to the base and joining or nearly joining the curves of the adjacent edges of the cylindrical portion, thus giving a pleasing appearance to the structure. Owing to the greater distance of the cylindrical portion from one end of the base than the other, the curves will unite less acutely at one end than at the other.

What I claim as my invention is—

The design for the frame of a machine, substantially as herein shown and described. 35

In testimony whereof I have hereunto subscribed my name this 6th day of January, A. D. 1892.

ALBERT SCHMID.
